[57] **CLAIM**

The ornamental design for a bathtub spout protective cover, as shown and described.

DESCRIPTION

FIG. 1 is a perspective view taken from the top, front and left side of a bathtub spout protective cover showing my new design;

FIG. 2 is a front elevational view thereof;

FIG. 3 is a left side elevational view thereof, the right side being a mirror image of the left side;

FIG. 4 is a top plan view thereof;

FIG. 5 is a rear elevational view thereof; and,

FIG. 6 is a bottom plan view thereof.

The broken line representation of surface ornamentation in FIGS. 1 through 4 is for purposes of illustration only and forms no part of the claimed design.
